UNITED STATES PATENT OFFICE

160,915

ANTENNA INSULATOR

Harley E. Arnold and George W. Saffran,
Toledo, Ohio

Application December 12, 1949, Serial No. 6,565

Term of patent 7 years

(Cl. D26—14)

To all whom it may concern:

Be it known that we, Harley E. Arnold and George W. Saffran, citizens of the United States of America, residing at Toledo, Lucas County, Ohio, have invented a new, original, and ornamental Design for an Antenna Insulator, of which the following is a specification, reference being had to the accompanying drawings, forming part hereof.

Fig. 1 is a side elevational view of an antenna insulator, showing our new design; and

Fig. 2 is a top plan view thereof.

We claim:

The ornamental design for an antenna insulator, as shown.

HARLEY E. ARNOLD.
GEORGE W. SAFFRAN.
